UNITED STATES PATENT OFFICE.

ANDREW J. BOTTORFF, OF SAWTELLE, CALIFORNIA.

BOAT.

1,330,109.

Specification of Letters Patent. Patented Feb. 10, 1920.

Application filed March 31, 1919. Serial No. 286,560.

To all whom it may concern:

Be it known that I, ANDREW J. BOTTORFF, a citizen of the United States, residing at Sawtelle, in the county of Los Angeles and State of California, have invented new and useful Improvements in Boats, of which the following is a specification.

My object is to make a boat and my invention consists of the novel features herein shown, described and claimed.

Figure 1 is a top plan view of a boat embodying the principles of my invention, the view being taken looking in the direction indicated by the arrow 1 in Fig. 2.

Fig. 2 is a side elevation looking in the direction indicated by the arrow 2 in Fig. 1.

Fig. 3 is a sectional detail on the lines 3—3 of Figs. 1 and 2 and looking in the direction indicated by the arrows.

Fig. 4 is an inner end view of one of the propellers as seen looking in the direction indicated by the arrow 4 in Fig. 3.

Fig. 5 is a fragmentary vertical longitudinal section on a plane parallel with Fig. 2 and on the line 5—5 of Fig. 1 and looking in the direction indicated by the arrows.

Fig. 6 is a fragmentary vertical cross section on the lines 6—6 of Figs. 1 and 2 and looking in the direction indicated by the arrow 6 in Fig. 5.

Fig. 7 is a fragmentary vertical sectional detail on the lines 7—7 of Fig. 6.

Fig. 8 is a fragmentary top view of that portion of the boat adjacent to the lever 33.

Fig. 9 is an end elevation of that portion of the boat comprising the lever 33 and its mounting, looked at in the direction of the arrow 9, Fig. 5.

The keel board 1 is a long straight plank. Blocks 2 and 3 are built up crosswise of the keel board 1 short distances on each side of the longitudinal center, said blocks being made in sections so the aggregate heights may be adjusted by adding or removing sections.

The gearing base 4 is a short plank mounted with its ends upon the blocks 2 and 3. Seats 5 and 6 are mounted upon springs 7 and 8 and the lower ends of the springs fit upon the ends of the base 4. Bolts 9 and 10 are inserted upwardly through the keel board 1 and through notches in the ends of the blocks 2 and 3 and through

the ends of the base 4 and through the springs 7 and 8, and nuts 11 and 12 are applied to the upper ends of the bolts to hold the parts removably together.

Posts 13, 14, 15 and 16 are secured to the base 4 and extend upwardly in parallel vertical positions. A board 17 is placed edge-wise upon the base 4 inside of the posts 15 and 16 and secured in place, and a similar board 18 is placed inside of the posts 13 and 14 and secured in place. The boards 19 and 20 are placed loosely upon the boards 17 and 18, and the boards 21 and 22 are placed upon the boards 19 and 20 and secured to the upper ends of the posts 13, 14, 15 and 16, so that the boards 19 and 20 will slide end-wise. Shafts 23 and 24 are mounted with their ends in the boards 19 and 20, spur gears 25 and 26 are mounted upon the shafts 23 and 24, pawl wheels 27 and 28 are fixed against the sides of the gears 25 and 26 inside of the board 19, and similar pawl gears 29 and 30 are fixed against the opposite sides of the gears inside of the board 20. A shaft 31 extends through the boards 21 and 22, and a spur pinion 32 is fixed upon the shaft in position to mesh alternately with the gears 25 and 26. The gears 25 and 26 run loosely either by turning upon the shafts 23 and 24, or by turning the shafts, and the gears 25 and 26 are spaced apart and so located that when the boards 19 and 20 are moved to the left, as in Fig. 5, the gear 25 meshes with the pinion 32 and the gear 26 is out of mesh, and when the boards are moved in the opposite direction the gear 26 meshes with the pinion 32 and the gear 25 is out of mesh.

The gear shifting lever 33 is mounted between the ends of the boards 17 and 18 upon a pivot 34, there being spacing collars upon each side of the lever to centralize the lever relative to the boards. A pin 35 connects the lever 33 to the boards 19 and 20. A stop 36 is fastened across the end faces of the boards 21 and 22 to limit the outward swing of the lever 33. Stop pins 37 and 38 are fixed in the upper edges of the boards 21 and 22 and stop blocks 39 and 40 are fixed to the boards a short distance from the pins 37 and 38. The lever 33 extends upwardly above the boards 21 and 22, and a block 41

is placed across the boards against the pins 37 and 38 and behind the lever 33, as shown in Figs. 5 and 6 to hold the lever 33 inwardly to slide the boards 19 and 20 to the right, as in Fig. 5, and to bring the gear 25 into mesh with the pinion 32.

When it is desired to reverse the direction of the shaft 31 the block 41 is moved to the other side of the lever, the lever 33 swung outwardly against the stop 36 and the block inserted between the lever and the blocks 39 and 40, thereby moving the boards 19 and 20 in the other direction and bringing the gear 26 into mesh with the pinion 32 and moving the gear 25 out of mesh.

The hand levers 42 and 43 are placed against the outer sides of the boards 17, 18, 19, 20, 21 and 22, and a pivot pin 44 is inserted through the lower ends of the levers 42 and 43 and through the boards 17 and 18. A handle 45 connects the upper ends of the hand levers 42 and 43, and rods 46 and 47 are mounted through the hand levers just above the pinion 32. Pawls 48 and 49 are mounted upon the rod 47 and pawls 50 and 51 are mounted upon the rod 46. The pawls 48 and 49 engage the pawl wheels 29 and 27, and the pawls 50 and 51 engage the pawl wheels 30 and 28. Horizontal elongated loops 52 are formed in the hand levers 42 and 43 to straddle the shaft 31, so that the levers may be vibrated transversely of the shaft.

One operator may sit upon the seat 5 and the other upon the seat 6 and both operators may grasp the handle 45 and work the handle to and fro to operate the pawls to drive the pawl wheels, and when the gear 25 is in mesh with the pinion 32 the boat will go one way, and when the gear 26 is in mesh with the pinion 32 the boat will go the other way.

The float supported propeller wheels 53 and 54 are fixed upon the ends of the shaft 31 outside of the hand levers 42 and 43 and extend outwardly in a straight line. The float supported propeller wheels 53 and 54 are substantially alike and each constructed as shown in Figs. 3 and 4.

A socket 55 is fixed upon the end of the shaft 31, four arms 56 extend radially from the socket, a ring 58 is secured to the arms concentric to the socket, intermediate arms 59 are secured to the ring 58, and a second ring 60 is secured to the arms 56 and 59. A plurality of cylindrical air tight compartments 61 is placed end to end against the arms 56, a spider 62 is placed against the outer face of the outer compartment 61, said spider 62 being substantially like the spider formed by the arms 56 and 59 and the rings 58 and 60, and rods 63 are inserted through the spiders outside of the compartments to hold the spiders to hold the compartments

in place. Blades 64 extend outwardly from the peripheries of the air tight compartments 61, the ends of the blades 64 being secured to the outer ends of the arms 56 and 59, and the blades being evenly spaced apart around the compartments. The air tight compartments may be made of sheet metal and of any desired diameter and thickness, and any desired number may be used, so that if one compartment became punctured the other compartments will not be affected.

Posts 65 and 66 extend upwardly from the keel board 1 just outside of the springs 7 and 8. Cleats 67 and 68 are secured along the upper outer edges of the keel board 1. Air tight compartments 69 and 70 are placed in rows upon the keel board 1 between the cleats and against the posts 65 and 66. Boards 71 and 72 are connected to the upper ends of the posts 65 and 66 by hinges 73 and 74 and have cleats 75 and 76 to engage the compartments 69 and 70, and bolts 77 and 78 extend upwardly through the extreme ends of the keel board 1 and through the outer ends of the boards 71 and 72, and nuts 79 and 80 are removably mounted upon the bolts, so that by removing the nuts the boards 71 and 72 may be swung upwardly to release the compartments 69 and 70, and so that by applying the nuts the compartments are securely held in place. The inner one of the compartments 69 and the outer one of the compartments 70 may be pointed so as to cut the water and the boat will run freely in the direction in which these compartments point.

Thus I have produced a boat consisting of a cheap, light, portable knock-down construction which is practically unsinkable and which cannot be capsized and can be readily and easily operated by one or two operators in any kind of sea.

Various changes may be made without departing from the spirit of my invention as claimed.

I claim:

1. A boat comprising a keel board, air tight compartments mounted upon the ends of the keel board, a propeller shaft rotatably mounted transversely of the boat, gearing for rotating the propeller shaft a hand lever for operating the gearing and propellers mounted on the outer ends of the shaft having propeller blades on their peripheries.

2. A boat comprising a keel board, air tight compartments mounted upon the ends of the keel board, a propeller shaft rotatably mounted transversely of the boat, a ratchet gearing for rotating the propeller shaft a hand lever for operating the ratchet gearing and float propellers mounted on the outer ends of the propeller shaft having propeller blades on their peripheries.

3. A boat comprising a keel board, air

tight compartments mounted upon the ends of the keel board, a propeller shaft rotatably mounted transversely of the boat, a ratchet gearing for rotating the propeller shaft, a hand lever for operating the ratchet gearing, float propellers mounted on the outer ends of the propeller shaft having pro-

peller blades on their peripheries and seats mounted on the keel board conveniently positioned relative to the hand lever.

10

In testimony whereof I have signed my name to this specification.

ANDREW J. BOTTORFF.
